LASTS

Stephen A. Makovski and Raymond Snape, Leicester, England, assignors to United Shoe Machinery Corporation, Boston, Mass., a corporation of New Jersey
Filed Mar. 19, 1962, Ser. No. 180,663
Claims priority, application Great Britain June 20, 1961
6 Claims. (Cl. 12—133)

This invention relates generally to lasts, and has particular reference to a last of the type which has means for enabling the last to be positioned automatically in a shoemaking machine.

In United States Patent No. 2,806,233, issued September 17, 1957 to Hubbard et al., there is disclosed a shoe last having a positioning plate disposed in the top of the heel part, said plate having formed thereon two sets of positioning surfaces, one set being disposed to position the last for heel part operations, the other set being disposed to position the last for forepart operations.

Although positioning plates of the type shown in the above-identified application have been found satisfactory for use with lasts for men's shoes, the shape of said positioning plate has not been found convenient for use with lasts for women's shoes, since such lasts have a relatively small bearing surface on the top of the heel part. For use with women's lasts, it is desirable that the positioning plate cover as much of the surface as possible to avoid distortion of the last by pressures applied thereto during shoe manufacturing operations.

A positioning plate of the type shown in the above-identified application has the further disadvantage that to accomplish the positioning operation, a relatively complex mechanism is required on the machine and in semi-automatic operations, where the last is fed to a machine by hand, the fitting of the last into the positioning mechanism is tedious and time consuming.

The object of the present invention is to provide a positioning plate particularly adapted for use with a last for ladies' shoes, in that it is adapted to cover substantially the entire heel and surface without overhanging the edges thereof.

A further object of the invention is to provide a last having a positioning plate with means disposed on the heel end for positioning the last for heel operations and means disposed in the forward end for positioning the last for forepart operations.

A further object of the invention is to provide a last having a positioning plate which is shaped to facilitate semiautomatic operations.

Other objects of the invention will be apparent to one skilled in the art from the following detailed description of a specific embodiment thereof.

In the drawing,

FIG. 1 is a perspective view of a last having a positioning plate embodying the features of the invention;

FIG. 2 is a view in section, partly in elevation, of a last embodying the features of the invention, which is mounted on a machine having means for positioning the last for heel part operations;

FIG. 3 comprises two views each of which may be considered as sections on line III—III of FIG. 2 illustrating the positioning for heel part operations of both right and left lasts embodying the features of the invention;

FIG. 4 is a view in section, partly in elevation, of a last of the type described, which is mounted on a machine having means for positioning the last for forepart operations; and,

FIG. 5 comprises two views, each of which may be considered as sections on line V—V of FIG. 4, illustrating the positioning for forepart operations of both right and left lasts embodying the features of the invention.

2

Referring to the drawing, there is illustrated a last 10 of the usual construction, and comprises a forepart 12 and a heel part 14 hinged together in any convenient manner. The heel part 14 has a flat upper surface 16 which is parallel to the heel feather line plane. A positioning plate 18 is secured to the surface 16 by means of the usual thimble or socket member 20 and a pin 22.

The positioning plate 18 is of substantial thickness, with the periphery being shaped to provide two sets of positioning faces, one set comprising surfaces 24 and 26 on the forward portions of the sides for positioning the last for forepart operations, the other set comprising surfaces 28 and 30 disposed on the rear portion of the plate for positioning the last for heel part operations.

In the illustrated embodiment the forepart positioning faces 24 and 26 are parallel to the toe-to-socket plane of the last, shown on the drawing as line T—T, and lie at equal distances on opposite sides thereof. The term "toe-to-socket plane" of the last, as used herein and in the claims is defined generally as a plane perpendicular to the forepart feather line plane and passing through the center of the thimble or socket hole and the foremost part of the toe.

The heel part positioning faces 28 and 30 are inclined to one another preferably at an acute angle and are so disposed angularly in relation to each other that a line bisecting the included angle between the faces is parallel to and coincides with the heel center line plane of the last. The term "heel center line plane," as used herein and in the claims, is defined as a plane perpendicular to the heel feather line plane which passes through the center of the thimble or socket hole and the rearmost portion of the periphery of the heel, substantially bisecting the heel feather line plane and is shown on the drawing as line H—H.

Hence, the line bisecting the angle between the heel positioning faces 28 and 30, hereinafter referred to as the heel positioning center line, is disposed at the same angle to the center line of the forepart positioning faces 24 and 26 hereinafter referred to as the forepart positioning center line, as the heel center line plane is disposed to the forepart center line plane. It is also apparent that the heel positioning center line and the forepart positioning center line intersect at the axis of the thimble in socket.

The rear end of the plate may be provided with a projection 32 for engagement with a retaining spring 34 to retain the last in the positioning mechanism of a machine as will appear hereinafter.

The above described positioning plate is adapted for use with both right and left lasts with the plate for a left last as seen in plan view being a mirror image of the plate for a right last.

To accommodate lasts with positioning plates of the type described above, a machine intended for performing operations on the heel end of the shoe may be provided with a positioning apparatus (see FIGS. 2 and 3) comprising a support 36, with thimble pin 38 extending upwardly from the support and a positioning abutment 40 disposed in the support in spaced relation to the thimble post. The abutment 40 has a pair of positioning surfaces 42 and 44 disposed at an angle to each other, said angle being equal to the angle between the heel positioning faces 28 and 30, and being so oriented that the bisector of said angle passes through the axis of the thimble post.

Hence when a last is assembled onto the positioning apparatus, the last is positioned by the apparatus in such a manner that the heel center line is disposed in a predetermined orientation in relation to the machine, with said orientation being the same with both right and left lasts.

A machine to perform operations on the forepart of a shoe carried by the above described last may be provided

with a positioning apparatus (see FIGS. 4 and 5) comprising a support 46 having a thimble pin 48 and a pair of positioning blocks 50 and 52 disposed thereon in spaced relation to receive the forward end of the last positioning plate therebetween. The inner surfaces of the blocks 50 and 52 are spaced equal distances on opposite sides of a line passing through the thimble post in coincidence with which it is desired to orient the toe-to-socket plane of the last. Hence, the toe end of both right and left lasts will be oriented in the same position in relation to the machine.

Since certain obvious changes may be made in the illustrative device without departing from the scope of the invention, it is intended that all matters contained herein be interpreted in an illustrative and not in a limiting sense.

Having thus described our invention, what we claim as new and desire to secure by Letters Patent of the United States is:

1. A last having positioning means formed on the upper portion of the heel part, said positioning means having surfaces on the forward portion thereof for positioning the last for forepart operations and surfaces on the rear portion thereof for positioning the last for heel part operations.

2. A last having an elongated positioning member disposed on the heel part, said member having a thimble hole extending therethrough, means on the positioning member on one side of the thimble hole for positioning the last for forepart operations and means disposed thereon on the opposite side of the thimble hole for positioning the last for heel part operations.

3. A last having an elongated positioning member disposed on the heel part, said member having a thimble aperture extending therethrough, means disposed thereon forwardly of the thimble hole for positioning the last for forepart operations and means disposed thereon rearwardly of the thimble hole for positioning the last for heel part operations.

4. A last having an elongated positioning member disposed on the heel part, said member having a pair of surfaces on the forward end thereof oriented in a predetermined position in relation to the forepart shape of the last for positioning the last for forepart operations, and a pair of surfaces on the rear portion thereof oriented in a predetermined manner in relation to the heel part shape of the last for positioning the last for heel part operations.

5. A last having an elongated positioning member disposed on the upper surface of the heel part and a socket in the heel part, said member having a pair of surfaces on the forward end which are parallel to a toe-to-socket plane of the last and disposed on opposite sides thereof for positioning the last for forepart operations and a pair of surfaces on the rear end of the member for positioning the last for heel part operations, a line disposed midway between said latter pair of surfaces lying on a heel center-line plane of the last.

6. A last having an elongated positioning member disposed on the upper surface of the heel part, said member having a socket disposed thereon, a first pair of side surfaces disposed forwardly of the socket for positioning the last for forepart operations, said first pair of side

25 surfaces being parallel to a toe-to-socket plane of the last and disposed an equal distance on opposite sides thereof, and a second pair of side surfaces disposed rearwardly of the socket for positioning the last for heel part operations, the side surfaces of said second pair being disposed at an angle to each other, the bisection of said angle lying on a heel center line plane of the last, whereby said bisected angle and a line midway between said first pair of surfaces intersect at the axis of the socket.
